UNITED STATES PATENT OFFICE.

ALBERT GUNKLE, DECEASED, LATE OF LA FAYETTE, INDIANA, BY MILLIE B. GUNKLE,
ADMINISTRATRIX, OF LA FAYETTE, INDIANA.

BOILER-FLUE.

1,082,119.

Specification of Letters Patent. Patented Dec. 23, 1913.

Application filed June 11, 1913. Serial No. 773,081.

To all whom it may concern:

Be it known that ALBERT GUNKLE, deceased, late a citizen of the United States, residing at La Fayette, in the county of 5 Tippecanoe and State of Indiana, did invent certain new and useful Improvements in Boiler-Flues, of which the following is a specification, reference being had to the accompanying drawings.

10 This invention relates to new and useful improvements in boiler flues and more particularly to novel means for securing the ends thereof to the flue sheet, the object of the invention being to provide flues of the 15 above character which can be readily placed in position and so arranged that the ends thereof will be securely held in place.

Another object of the invention is to provide a device of the above character which 20 will possess advantages in points of efficiency and durability, is inexpensive of manufacture and at the same time is simple in construction and operation.

With the above and other objects in view, 25 the invention consists in the novel features of construction and the combination and arrangement of parts to be hereinafter more fully described, pointed out in the claim and shown in the accompanying drawings, 30 in which—

Figure 1 is an end view of a flue sheet showing the ends of the flues in position; and Fig. 2 is an enlarged longitudinal sectional view taken through one of the flues. 35 Fig. 3 is a similar view illustrating a modified form of securing means.

Referring more particularly to the drawings, 1 indicates the flue sheet and 2 the flue which may be of the ordinary construction, 40 or any other suitable construction desired. The flue sheet 1 is provided with a suitable opening 3 adapted for the reception of the end of the flue and is further provided with an annular recess 4 encircling said opening. 45 The recess 4 is provided with a vertical wall 5 and an inclined wall 6 which tapers outwardly from the inner end of the recess 4 to the outer end of the opening 3.

In securing the end of the flue 2 in position, it is first provided with a plurality of slits 7 and then bent outwardly and downwardly into the recess 4, the annular outer end of the tube conforming to the shape of the interior of the recess and engaging the

inclined wall 6. From this it will be seen 55 that in case the flue sheet 1 expands outwardly, the end of the flue will tightly engage within the recess 4 and limit the expansion of the flue sheet.

In Fig. 3, I have illustrated a slightly 60 modified form of securing means wherein I provide a ring 8 which is adapted to be inserted within the recess 4 after the end of the flue has been placed therein. The inner face of the ring 8 is provided with an 65 inclined wall 9 which will conform to the position of the end of the flue, and terminating the inner edge of the ring into a suitable point 10 whereby the ring may be readily driven into the recess 4 after the 70 end of the flue has been placed in position. It will be understood that the friction between the ring and the wall of the recess and the end of the flue will be sufficient to securely hold the ring in position which in 75 turn will prevent the removal of the end of the flue from the recess. In this manner, the outwardly bent end of the flue will be securely held in place within the recess.

From the above description taken in connection with the accompanying drawings, 80 it will be readily apparent that I have provided simple and durable means for securely fastening the ends of flues to the flue sheet. It will also be apparent that the flue 85 is so fastened that it may be readily removed, if desired, and it will also be apparent that the device is extremely simple in construction and can be manufactured at a comparatively low cost. 90

While I have shown and described the preferred form of my invention, it will be obvious that various changes in the details of construction and in the proportions may be resorted to for successfully carrying my 95 invention into practice, without sacrificing any of the novel features or departing from the scope of the appended claim.

What I claim is:—

The combination with a flue sheet having 100 an opening and further provided with an annular recess encircling said opening, said recess having a vertical outer wall and an inclined wall which tapers outwardly from the inner ends of the recess to the outer end 105 of said opening, of a flue having its end provided with a plurality of slits and bent outwardly and downwardly into said recess,

the end of the flue conforming to the inclination of the inner wall, and a ring provided with a sharpened inner edge and disposed within the recess between the end of 5 the flue and the outer wall to frictionally engage the same and securely hold the end of the flue in place.

In testimony whereof, I hereunto affix

my signature in the presence of two witnesses.

*MILLIE B. GUNKLE,
Administratrix of the estate of Albert
Gunkle, deceased.*
